UNITED STATES PATENT OFFICE.

MARY A. PATTERSON, OF AMHERST, MASSACHUSETTS.

DESIGN FOR A LINGERIE-RIBBON TIP.

52,587.

Specification for Design.

Patented Oct. 15, 1918.

Application filed February 21, 1918. Serial No. 218,588. Term of patent 14 years.

To all whom it may concern:

Be it known that I, MARY A. PATTERSON, a citizen of the United States, residing at Amherst, in the county of Hampshire and State of Massachusetts, have invented a new, original, and ornamental Design for Lingerie-Ribbon Tips, of which the following is a specification, reference being had to the accompanying drawing, forming part hereof.

gerie ribbon equipped with my new design of lacing tip; and,

Fig. 2 is a perspective view on an enlarged scale, showing one of the tips, detached.

I claim:

The ornamental design for a lingerie ribbon tip, as shown.

MARY A. PATTERSON.
